UNITED STATES PATENT OFFICE.

VINCENT G. APPLE, OF DAYTON, OHIO.

ART OF ARMATURE CONSTRUCTION.

1,276,857.

Specification of Letters Patent. Patented Aug. 27, 1918.

Application filed February 14, 1918. Serial No. 217,152.

To all whom it may concern:

Be it known that I, VINCENT G. APPLE, a citizen of the United States, residing at Dayton, in the county of Montgomery and State of Ohio, have invented certain new and useful Improvements in the Art of Armature Construction, of which the following is a specification.

My invention relates to the art of armature construction and has especial reference to a method of welding armature conductors together in pairs and simultaneously to a commutator segment.

One of the objects of my invention is to provide a new and improved method of joining the terminal ends of armature conductors together and simultaneously to appropriate commutator segments or bars.

Other and further objects of my invention will become readily apparent from a consideration of the following description when taken in conjunction with the drawings, wherein:

Figure 1 is an end view of an armature and commutator showing the manner of connecting the armature terminals to the commutator bars.

Fig. 2 is an enlarged section taken on line 2—2 of Fig. 1.

Fig. 3 shows a fragment of the completed work.

Fig. 4 is a conductor bar connector.

In all the views the same reference characters indicate similar parts.

In the example illustrated the armature conducting bars 5 and 6 constitute a pair adapted for connection together and to a commutator bar 7. These conductors are relatively thin and wide, a most excellent proportion to prevent loss by self induction.

There is some difficulty, however, in joining the terminal ends 5' and 6' together. I therefore provide a connector 8 (see Fig. 4) having a cross section in outline resembling the letter H. This connector is preferably made of copper and is slipped in between the terminals 5' and 6', as shown in Figs. 2 and 3. It holds the bars in radial alignment and serves as a filler. The commutator bars 7 are grooved at their rear ends to receive the bar 6', edge on.

The armature core 9 and the end members 10 and 11 are mounted on the shaft 12.

To weld the terminals together and to the commutator bars, a ring 14, which may have an outline rectangular in shape, and which

may be lined with insulating material 15, is slipped over the rear end of the commutator and the screw 16 is turned down on to a block 17. A conducting strip 18, having, preferably, the shape of the conductor connector 8, but preferably of substantially non-weldable metal, at the relatively low temperature at which copper softens, is placed over the top edge of the terminal 5' and the screw tightened. The lower edge of the terminal 6' having been placed in a groove cut into the rear end of the commutator bar 7.

The conducting strip 18 is connected to a source of current supply, not shown, by the wire 19.

Another ring 20 having an insulating lining 21, is placed over the front end of the commutator and the screw 22 is tightened down on the commutator bar 7, with which the selected pair of terminals 5' and 6' are connected. The wire 23 is connected to the source of current supply and the circuit closed. So soon as the terminals 5', 6' and the connector 8 begin to soften, pressure is applied to complete the weld. This may be done by turning the screw 16.

Other welding apparatus, materially differing from that shown, may be used. That shown is of the simplest conventional form.

After one set of joints have thus been made, the next adjacent members are likewise welded together and so on, until each pair of terminals has been welded to its commutator bar until all have been properly joined.

Having described my invention, what I claim is:

1. The art of joining radially disposed pairs of spaced-apart armature terminals to commutator segments, which consists in placing an alining filler block between the terminals; placing one edge of one of the pair of terminals in contact with a commutator bar; passing a current of electricity through the commutator bar, the terminals and the block, and applying pressure as the metal softens, to weld the four elements together.

2. The art of joining relatively wide and thin, radially disposed, spaced-apart armature terminals to commutator segments which consists in preparing a filler guide-block which will hold the terminals in a common radial plane; placing the block

between adjacent terminals of a pair of terminals; placing one of said terminals in contact with a commutator bar; placing a substantially non-weldable electrically conducting block in contact with the other terminal connecting said commutator bar, said terminals and blocks in an electric circuit; closing said circuit and applying pressure to the parts to be welded.

10 3. The art of joining radially-disposed

pairs of spaced-apart armature terminals after they are in place on a core of the armature which consists in placing an alining filler block between the terminals; welding both terminals to the filler, then welding the terminals and filler to a commutator bar.

In testimony whereof I hereunto set my hand.

VINCENT G. APPLE.
